UNITED STATES PATENT OFFICE.

JOHN CUMMINGS, OF GRAND RAPIDS, MICHIGAN.

CARRIER FOR CANS, CASKS, &c.

No. 878,358.

Specification of Letters Patent.

Patented Feb. 4, 1908.

Application filed May 10, 1907. Serial No. 373,009.

To all whom it may concern:

Be it known that I, JOHN CUMMINGS, a citizen of the United States of America, residing at Grand Rapids, in the county of Kent 5 and State of Michigan, have invented certain new and useful Improvements in Carriers for Cans, Casks, &c.; and I do hereby declare the following to be a full, clear, and exact description of the invention, such as will enable 10 others skilled in the art to which it appertains to make and use the same.

My invention relates to improvements in carriers for cans, casks, barrels and other like articles; and its object is to provide the same 15 with means whereby a can, cask, barrel or other like receptacle may be readily picked up and transported from place to place, and again deposited, as occasion may require.

My invention consists essentially of an 20 axle bent to embrace the article to be carried, wheels journaled on bearings oppositely projecting from the ends of the bent portion of the axle, a lever also bent to embrace the article and adapted to engage hooks on the article and also pivotally mounted on the axle, 25 a handle, and means for securing the lever to the handle; and in the combination and arrangement hereinafter more fully described and particularly pointed out in the claims, 30 reference being had to the accompanying drawing, in which:

Figure 1. is a side elevation of a device embodying my invention with one wheel removed; Fig. 2. the device in plan view; Fig. 35 3. an elevation of the can, detached; Fig. 4. an enlarged detail of one end of the lifting lever; Fig. 5. enlarged detail of the means for detachably securing the lever to the handle; and, Fig. 6. a front elevation of the 40 transverse member of the handle.

Like numbers refer to like parts in all of the figures.

1—1 represent a pair of wheels of suitable dimensions and journaled on an axle 2 having the middle portion bent to embrace the article to be carried, being shown in semi-circular form to embrace the can 11; 3 is a handle attached to the middle of the axle for manually propelling the device. The end of 45 this handle is provided with a transverse member 4, on the ends of which are hooks 5 and 6.

7 is a lever also bent in semi-circular form to embrace the can 11, and having its ends 50 extended above the respective ends of the semi-circular portions of the axle 2 and piv-

otally mounted thereon as at 8. This lever is provided with bell crank arms 10 extending laterally therefrom near the pivots and each having a divided outer end to engage and support hooks 9 attached to the opposite sides of the can or other article to be transported by the device. The middle portion of this lever 7 is extended beyond the axle 2 and above the handle 3 and is provided with 55 an upwardly extended and recessed portion 12 to embrace and detachably engage the handle 3 whereby the same is braced against lateral strains, and this portion 12 is also provided with a hook 13 pivoted thereto and 60 adapted to extend beneath the handle 3 and hold the lever 7 detachably engaged therewith.

14 is a downwardly projecting leg extending beneath the handle and adapted to engage 65 the ground and support the bent portion of the axle in substantially a horizontal position.

By releasing the lever 7 from the handle and turning the same upward upon its pivots 8, the can will be carried backward and lowered to near the ground and the stops 15 will hold the lever in a substantially vertical position with the can slightly raised from the ground. By raising the handle 3, the can 80 will be deposited on the ground and the open end of the arms 10 detached from the hooks 9. The reverse movements will of course raise the can to supported position between the ends of the axle and the wheels, with the 85 hooks 9 slightly forward of the pivots 8, which tends to press the lever 7 down on the handle 3 and thus maintain the same in place until purposely raised to carry the can 90 backward and downward, and also putting 95 a small fraction of the load on the handle.

A broom and shovel or other like tools for gathering material and placing the same in the can may be carried on the lever 7 with their handles resting in the hooks 5 and 6. 100

The device shown is especially adapted for picking up, transporting and depositing cans for garbage of various kinds, and particularly adapted for use in street cleaning operations, but obviously not limited to use in conjunction with cans only, as it would operate as well with casks or any other suitable receptacles provided with hooks or trunnions 9.

What I claim is:

1. The combination of an axle bent in a 110 semi-circle, oppositely projecting journals on said axle, wheels mounted on the journals, a

handle attached to the axle, a lever bent in semi-circular form and having its ends pivoted to the axle and also having arms provided with forked ends to engage projections

5 on a can or other article to be carried, and means for securing the lever to the handle.

2. The combination of an axle bent to embrace a can or other article to be carried, wheels journaled on the axle, a handle attached to the axle, a lever also bent to embrace said can, and pivoted to the axle, bell crank arms on the lever having divided ends to engage projections, a stop to limit the backward movement of the lever, and means 10 for attaching the lever to the handle.

3. The combination of a can having hooks at its opposite sides; an axle bent to embrace the can, a handle attached to the axle, a lever bent to embrace the can and pivoted on the axle, lateral arms on the lever adapted 20 to engage the hooks and support the can, and means for detachably securing the lever to the handle.

4. The combination of an axle bent in semi-circular form at the middle, wheels journaled on the ends of the axle, a handle attached to the axle, a lever also bent in semi-circular form and pivoted to the axle, bell crank arms on the lever, a stop to limit 25 the rearward movement of the lever, an up-

ward extension of the lever having a recess to receive the handle and a hook on the lever to engage the handle and hold it in the recess.

5. The combination of a can having hooks 35 at its opposite sides, an axle bent to embrace the can, wheels journaled on the axle, a lever bent to embrace the can and pivoted on the axle, bell crank arms on the lever and having divided ends to engage the hooks on the can, 40 stops on the lever to engage the axle and limit the backward movement of the lever, an upward extension of the lever having a recess to receive the handle and a hook pivoted on the extension and detachably 45 engaging the handle.

6. The combination of an axle bent to embrace the can, a handle attached to the axle, a transverse member on the handle, hooks on the ends of said member, a lever 50 bent to embrace a can and pivoted to the axle, arms on the lever and adapted to support a can, and means for detachably connecting the lever to the handle.

In testimony whereof I affix my signature 55 in presence of two witnesses.

JOHN CUMMINGS.
